UNITED STATES PATENT OFFICE.

EDWIN WARREN, OF CHICAGO, ILLINOIS.

HOSE-SUPPORTER.

No. 868,044.

Specification of Letters Patent.

Patented Oct. 15, 1907.

Application filed March 29, 1907. Serial No. 366,314.

To all whom it may concern:

Be it known that I, EDWIN WARREN, a citizen of the United States, residing at Chicago, in the county of Cook and State of Illinois, have invented certain new and useful Improvements in Hose-Supporters, of which the following is a specification.

My invention relates to hose supporters and has special reference to that class having a dependent loop of webbing, either elastic or unyielding, to which a 10 clasp is attached, said clasp comprising two component parts which co-act to clamp and hold a fold of the fabric to be supported.

The chief objects of my invention are to provide a simple and efficient clasp for the purpose stated; to 15 furnish a durable garment clasp that will present a yielding surface to the fabric gripped thereby so that the tendency to abrasion of the material will be reduced to a minimum; and to produce a device that can be easily and therefore economically manufactured.

20 A further object of my invention is to provide a garment fastener in which the component members can be readily and easily engaged, and to furnish one of the co-acting members with a convenient finger hold that will enable the user to quickly disengage the fabric 25 from its hold.

I accomplish the above and other minor results by means of the device illustrated in the accompanying drawing, which forms a part of this specification and in which:—Figure 1 is a view of the pendent portion of a 30 hose supporter having my improved gripping clasp attached thereto; Fig. 2 is a side view of the gripping member; Fig. 3 is a vertical section of the button and base plate; Fig. 4 is a cross section on the line 4—4 of Fig. 3; and Fig. 5 is a vertical section of a modified form 35 of button.

Referring to the drawing in detail, the numeral 5 indicates a strap of webbing or other suitable material attached to a metal link 6, from which depends a tape 7, looped through the lower slot of said link. One end of 40 said tape is provided with a button 8 having an oval contour, and consisting of a stem 9, secured by riveting to a base plate 10, said plate being provided with slots in the usual manner to facilitate securing the tape thereto. The said stem is formed of an eyelet, oval in 45 cross section and provided with a marginal lip 11 at its free end. The stem is surrounded with a layer of elastic material 12, preferably rubber, and the said lip having a greater diameter than the stem causes the elastic covering to bulge laterally and thus form a head for the 50 button. Upon the opposite end of said tape 7 is secured a gripping member or clasp 14, in the form of a flattened hook. The tape is looped through a slot 15 and the end secured by stitching to the main part of the tape. This hook is preferably formed of a metal plate 55 and is furnished with a gripping slot 16 which narrows

toward the inner end, and along the margin of said slot upon one side of the hook is a retaining ridge or flange 17.

Near the extremity of the hook is a rounded projection or tooth 18 and upon the opposite margin of the slot is a corresponding notch or depression 19. Along the 60 outer margin of the hook is a raised rib or ridge 20, upon the side of the hook opposite to that which carries said retaining ridge. The ridge 20 is for the purpose of affording a grasp for the finger when disengaging the hook. The function of said raised margin 17 is to aid 65 the hook to retain its grip when in engagement with its co-acting member, as shown in Fig. 1, said margin exerting pressure upon the fabric which is included between the co-acting members. The tooth 18 also has a special retaining function and the inclined sides of the 70 slot 15 produce a wedging action upon the button stem with the result that when the hook is engaged therewith it will retain its hold under the ordinary forces to which it will be subject when in use.

In Fig. 5 is shown a modified form of button the eyelet 75 which forms the hollow stem illustrated in Fig. 3 being replaced by a solid stud 21, oval in cross section, and secured to the base plate by riveting in the usual manner and having an enlarged head 22. The covering 23 of the button is composed of soft rubber which is 80 molded therein and is continuous over the head of the stud.

It is obvious that certain changes as fall within the scope of the appended claims may be made in the details of construction of my improved clasp as herein disclosed without departing from the spirit and scope 85 thereof, and I do not wish, therefore, to be limited to the precise construction set forth.

Having thus described my invention what I claim is:—

1. In a clasp for a hose-supporter, the combination of a 90 button, a yielding covering for the button, and a hook adapted to engage the stem and head of said button, said hook being furnished with a retaining ridge upon one side and a finger hold upon the opposite side.

2. In a clasp for a hose supporter the combination of a

base plate, a button attached to said plate, the stem of

said button being oval in cross section, and a gripping

member in the form of hook provided with a tapering slot

adapted to engage the stem of said button, the end of said

hook being provided with a projecting tooth, and the op-

posing margin having a depression corresponding with said

tooth.

3. In a fastener for a hose-supporter, the combination

of a base plate, an oval button attached to said plate by

an oval support, an elastic covering for said button, and a

gripping member adapted to engage the stem of said but-

ton, said gripping member being in the form of a hook, pro-

vided with a tooth and a corresponding marginal depres-

sion, a retaining ridge upon one side, and a marginal finger

hold in the form of a ridge upon the opposite side of said

gripping member.

4. In a clasp for a hose supporter, the combination with

a base plate provided with a button, of a gripping member

90

100

110

provided with an engaging slot having tapering margins, a tooth upon one margin and a corresponding depression upon the opposite margin, a retaining ridge upon one face of said gripping member and a finger hold upon the other.

5. In a clasp for a hose supporter, the combination with a gripping member in the form of a hook, of a coöperating member having a base plate, a button secured to said plate by an oval eyelet, and an elastic covering for the button.

6. In a clasp for a hose supporter, the combination with 10 a gripping member in hook form, of a button comprising a

base-plate, an oval stud secured to the plate, and an elastic layer molded upon said stud to form a continuous layer therefor.

In testimony whereof I affix my signature in the presence of two witnesses.

EDWIN WARREN.
